US00D520960S

(12) **United States Design Patent** (10) **Patent No.:** **US D520,960 S**
(45) **Date of Patent:** **** May 16, 2006**

(54) **VACUUM EQUIPMENT**

(75) Inventors: **Shigekazu Nagai**, Tokyo-to (JP);
Yoshiharu Ito, Toride (JP); **Takashi Toyama**, Moriya (JP)

(73) Assignee: **SMC Kabushiki Kaisha**, Tokyo (JP)

(**) Term: **14 Years**

(21) Appl. No.: **29/206,740**

(22) Filed: **Jun. 1, 2004**

(30) **Foreign Application Priority Data**

Dec. 1, 2003 (JP) 2003-035694

(51) **LOC (8) Cl.** **13-03**

(52) **U.S. Cl.** **D13/158**

(57) **CLAIM**

The ornamental design for a vacuum equipment, as shown.

DESCRIPTION

FIG. 1 is a top, front and left-side perspective view of a vacuum equipment showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken line showing of the environment is for illustrative purposes only and forms no part of the claimed design.
